UNITED STATES PATENT OFFICE.

CHARLES C. BOYD, OF WESTBURY, NEW YORK.

ROTARY ENGINE.

1,199,235.

Specification of Letters Patent. Patented Sept. 26, 1916.

Application filed July 21, 1915. Serial No. 41,046.

To all whom it may concern:

Be it known that I, CHARLES C. BOYD, a citizen of the United States of America, and a resident of Westbury, Nassau county, and 5 State of New York, have invented certain new and useful Improvements in Rotary Engines, of which the following is a specification, reference being had to the accompanying drawings, forming a part thereof.

- 10 My invention relates to rotary internal combustion engines, and has for one object to provide an improved device of this character that shall be particularly adapted for the propulsion of motor vehicles.
- 15 Other objects and advantages of my invention will be set forth hereinafter, and in order that my invention may be thoroughly understood I will now proceed to describe the same in the following specification and 20 then point out the novel features thereof in appended claims.

Referring to the drawings: Figure 1 is an end elevation with a portion of the cooling fan broken away, of a rotary engine arranged and constructed in accordance with 25 my invention. A transverse sectional elevation of the engine is shown in Fig. 2. Fig. 3 is a sectional plan view of the rotor. Fig. 4 is a sectional elevation in a longitudinal plane. Fig. 5 corresponds to a portion of Fig. 2, but shows the coöperating pistons in other positions. Fig. 6 is a sectional detail through the inlet port. Figs. 7 and 8 are sectional views, taken respectively on 30 the lines 7—7 of Fig. 2 and 8—8 of Fig. 5. Fig. 9 is a sectional detail of the rotor packing on a larger scale.

10 designates the stator, and 11 the rotor of a rotary engine which is equipped with a carbureter 12, a magneto 13 and has an inlet pipe 14, an exhaust pipe 15, a water jacket 16, a water reservoir 17 connected thereto, and a cooling fan 18.

The stator 10 is divided in a central transverse plane, into sections 19 and 20 which are circular in form and are secured together by any suitable means, such as bolts 21, which extend through suitable holes in flanges 22. The body of the stator has the 45 form of a torous ring and has outwardly extending lugs 23 by which it may be supported in a well known manner. Integral with the body are bearing brackets 24 having bearings 25 in which a shaft 26 is rotatively mounted.

The rotor 11 has a central hub 27 which

is keyed or otherwise secured to the shaft 26, and a radial disk 28 which constitutes the body of the rotor. Projecting radially beyond the circumference of the disk 28 are a 60 pair of diametrically opposite projections 30 and 31 and secured to these projections are a pair of revolving pistons 32 and 33.

The stator furthermore, comprises central hubs 34—34 which closely fit onto the rotor hub 27 and form bearings therefor, and radial webs 35—35, and 36—36 which connect the ring-shaped body to the hubs. The arrangement of parts is such that the rotor disk 28 fits closely in a thin annular space 70 formed between the webs 35 while the pistons 32 and 33 fit closely and are adapted to slide in an annular chamber 38 which is circular in cross-section as clearly shown in Fig. 4. The projections 30 and 31 of the 75 rotor disk extend into the ring-shaped chamber 38, as shown in Fig. 2, and steel packing ring segments 39 are utilized, as clearly shown in Figs. 4 and 9, for sealing the joint between the rotor and the stator 80 and between the revolving pistons 32 and 33 at the circumference of the chamber 38.

The webs 36 of the stator form parts of the outer shell which correspond in shape to the inner shell already described and are 85 spaced from it to produce the water jacket 16. The chamber 38 has an outlet port 40 which communicates with the exhaust pipe 15 as shown in Fig. 2, and at a point almost opposite the outlet port it opens into a cylinder 41. Within the cylinder is a sleeve 42 having a piston 43 at its inner end and within the sleeve is a piston 44. The sleeve 42, together with the piston 43, has secured to it a pair of rods 45 which extend outwardly through suitable packing in the end of the cylinder and are joined by a yoke 46. 90

The piston 44 has a single piston rod 47 which also extends through a suitable packing in the cylinder and through a bearing 48 100 in the yoke 46.

As clearly shown in Figs. 1 to 4, cams 50 and 51 are secured to a rotatable cam shaft 52 which is operatively connected to the engine shaft 26 by gears 53 and 54. Each of the cams has a pair of cam slots 55 near its periphery with which a pair of rollers 56 co-operate. These rollers are mounted on the arms of forks 57 which extend over the edges of the cams, as shown in Fig. 4. Actuating rods 58 and 59 are connected to the forks 110 and are moved in response to the cams 50

and 51 respectively. A yoke 60 connects the outer end of the piston rod 47 with the actuating rod 58, while the rods 45 are connected to the actuating rod 59 by the yoke 46 which has a projection 61 for the purpose. Thus, the pistons 43 and 44 are moved in response to the cams 50 and 51.

The pistons 43 and 44 are respectively provided with check valves 63 and 64 which open oppositely and are held closed by suitable springs 65 and 66, except when they are opened as hereinafter explained.

The cylinder 41 is provided with an outer casing 67 which is spaced from the cylinder 16 and constitutes a portion of the water jacket 16. At the upper end of the cylinder 41 the water jacket is connected by a pipe 68 to the water reservoir 17, the tank being also connected to the water jacket by a pair of ports 69.

The inlet pipe 14 which leads from the carburetor 12, is connected to the cylinder 41 at its outer end, through a check valve 70 as clearly shown in Fig. 6, the carburetor being provided with an air inlet 71 and secured to the stator, as shown in Fig. 4.

The magneto 13 is conveniently mounted on one of the bearings 25 and is operatively connected to the shaft 26 by gears 72.

30 The sleeve 42 is arranged to slide inwardly into the position shown in Fig. 2 and to temporarily constitute a complete barrier in the ring chamber 38. The cams 50 and 51 are so constructed that the piston 44 is close to the piston 43 when the latter is in its extreme inner position as shown in Fig. 2 and is separated materially therefrom when the piston 43 is at the opposite end of its stroke as shown in Fig. 5.

40 The operation of the engine is as follows:—Assuming that the shaft 26 is rotating in a counterclockwise direction (see Fig. 2), the pistons 32 and 33 are continuously revolving about the axis of the shaft 45 as they slide in the annular chamber 38 which, as already pointed out, is circular in cross-section. The cams are timed in their action relative to the rotor so that the piston 43 moves into the position shown in Fig. 2 immediately following each of the revolving pistons 32 and 33 in its movement across the opening into the cylinder 41. The speed of the piston 43 and the sleeve 42 is sufficient to overtake the revolving piston 33, bringing a stem 80 of the check valve 63 into engagement with a beveled end surface 81 of the piston. This engagement causes the check valve to open in opposition to the spring 65 and admits an explosive mixture, which has just been highly compressed between the pistons 43 and 44, into the small space between the piston 43 and the revolving piston 33. Into this space extends a spark plug, or other ignition device 82, which is timed in a well-known manner, to

fire the explosive mixture. The force of the explosion reacts against the piston 44 but produces useful work by acting upon the surface 81 of the revolving piston 33 which continues to move with the rotor which it is driving.

When the revolving piston 32 moves into the position occupied by the revolving piston 33 in Fig. 2, the action is repeated, and when the revolving piston 33 passes the opening 40 into the exhaust pipe 15, the burnt gases are permitted to escape.

The remainder of the cycle, with reference to the cylinder 41 and the pistons 43 and 44, will be readily understood, a new charge being drawn into the cylinder above the piston 44 during the stroke which brings the parts into the position shown in Fig. 2. This charge is slightly compressed during the reverse stroke and is forced into the space between the pistons through the check valves 64 when the pistons occupy the positions shown in Fig. 5. The charge thus pocketed between the pistons is highly compressed while another charge is being drawn in behind the piston 44.

Various structural modifications may be effected within the spirit and scope of my invention, and I intend that only such limitations be imposed as are indicated in the appended claims.

What I claim is:

1. A rotary internal combustion engine comprising an annular chamber, a revolving piston therein, an exhaust port communicating with the chamber at one side, a cylinder opening into the chamber at the opposite side, a piston operating in the cylinder and having a check valve actuated by the revolving piston, and means for compressing an explosive mixture back of the piston in the cylinder.

2. A rotary internal combustion engine comprising an annular chamber, a pair of revolving pistons therein, an exhaust port communicating with the chamber at one side, a cylinder opening into the chamber at the opposite side, a piston operating in the cylinder and having a check valve directly actuated by the revolving pistons, and means for compressing an explosive mixture back of the piston in the cylinder.

3. A rotary internal combustion engine comprising an annular chamber, a pair of revolving pistons therein, an exhaust port communicating with the chamber at one side, a cylinder opening into the chamber at the opposite side, a piston operating in the cylinder and having a check valve adapted to be controlled by the revolving pistons, and a second piston in the cylinder adjacent to the first for compressing an explosive mixture therein.

4. A rotary internal combustion engine comprising an annular chamber, a pair of

revolving pistons therein, an exhaust port communicating with the chamber at one side, a cylinder opening into the chamber at the opposite side, a sleeve piston operating 5 in the cylinder and having a valve in its lower end, means for reciprocating the sleeve piston to periodically enter the annular chamber and constitute a barrier therein, and means for compressing an explosive 10 charge in the cylinder back of the piston, said valve being adapted to be opened by the revolving pistons in the chamber.

5. A rotary internal combustion engine 15 comprising an annular chamber, a pair of revolving pistons therein, an exhaust port communicating with the chamber at one side, a cylinder opening into the chamber at the opposite side, a sleeve piston operating 20 in the cylinder and having a valve in its lower end, means for reciprocating the sleeve piston to periodically enter the annular chamber and constitute a barrier therein, and a second piston within the 25 sleeve piston and co-operating therewith to compress an explosive mixture, said valve being adapted to be opened by the revolving piston in the chamber.

6. A rotary internal combustion engine 30 comprising a combustion chamber, a cylinder adjacent thereto, a sleeve piston in said cylinder having a check valve at its inner end and adapted to move into and out of the combustion chamber, and means 35 for opening the check valve in the sleeve piston at the inner end of its stroke.

7. A rotary internal combustion engine comprising a combustion chamber, a cylinder adjacent thereto, a sleeve piston in 40 said cylinder having a check valve at its inner end and adapted to move into and out of the combustion chamber, and a second piston within the sleeve piston having an oppositely-arranged check valve and adapt- 45 ed to compress an explosive mixture in the sleeve piston.

8. A rotary internal combustion engine comprising a combustion chamber, a cyl-

inder adjacent thereto, a sleeve piston in 50 said cylinder having a check valve at its inner end and adapted to move into and out of the combustion chamber, a second piston within the sleeve piston having an oppositely-arranged check valve and adapted to 55 compress an explosive mixture in the sleeve piston, and means for opening the check valve in the sleeve piston to permit the compressed charge to flow from the piston into the combustion chamber.

9. A rotary internal combustion engine 60 comprising an annular combustion chamber, a revolving piston therein, a cylinder adjacent thereto and adapted to communicate therewith, a pair of pistons operating therein, and means for reciprocating the pistons with 65 strokes of unequal length whereby said pistons are brought near together at one end of their strokes and materially apart at their opposite ends.

10. A rotary internal combustion engine 70 comprising an annular combustion chamber, a rotary piston therein, a cylinder adjacent to the combustion chamber, a pair of pistons operating therein, means for reciprocating the pistons in said cylinder, in like directions but with strokes of unequal length, whereby said pistons are brought near together at the inner ends of their strokes and materially apart at the outer ends of 75 their strokes.

11. A rotary internal combustion engine comprising a combustion chamber, a rotary piston therein, a cylinder adjacent to the combustion chamber, a pair of pistons operating therein, means for reciprocating the 80 pistons in said cylinder, in like directions but with strokes of unequal length, whereby said pistons are brought near together at the inner ends of their strokes and materially apart at their opposite ends, and oppositely disposed check valves in said reciprocatory pistons.

In witness whereof, I have hereunto set my hand this 20 day of July, 1915.

CHARLES C. BOYD.
